UNITED STATES PATENT OFFICE.

WILLIAM A. STARCK, OF MILWAUKEE, WISCONSIN, ASSIGNOR TO BADGER MANUFACTURING CORPORATION, OF MILWAUKEE, WISCONSIN, A CORPORATION OF DELAWARE.

DESIGN FOR AN AUTOMOBILE BUMPER BAR.

Application filed October 15, 1927. Serial No. 23,759. Term of patent 7 years.

To all whom it may concern:

Be it known that I, WILLIAM A. STARCK, a citizen of the United States, residing at Milwaukee, in the county of Milwaukee and State of Wisconsin, have invented a new, original, and ornamental Design for Automobile Bumper Bar, of which the following is a specification, reference being had to the accompanying drawing, forming a part thereof.

Fig. 1 is a perspective view of a bumper bar.

Fig. 2 is an enlarged perspective view of a section of the bumper bar showing my new design.

I claim:

The ornamental design for an automobile bumper bar as shown.

In witness whereof, I have hereunto subscribed my name.

WILLIAM A. STARCK.
